S. W. WOMACK

BEDSTEAD DISPLAY RACK

Filed Jan. 8, 1925

Patented Apr. 27, 1926.

UNITED STATES PATENT OFFICE.

SAMUEL W. WOMACK, OF WICHITA FALLS, TEXAS.

BEDSTEAD-DISPLAY RACK.

Application filed January 8, 1925. Serial No. 1,227.

To all whom it may concern:

Be it known that I, SAMUEL W. WOMACK, a citizen of the United States, residing at Wichita Falls, in the county of Wichita 5 and State of Texas, have invented certain new and useful Improvements in Bedstead-Display Racks; and I do declare the following to be a full, clear, and exact description of the invention, such as will enable others skilled in the art to which it appertains to 10 make and use the same.

My invention aims to provide an extremely simple and inexpensive, yet a very desirable and efficient display rack for holding 15 the head or foot sections, or both, of bedsteads, the device being of such nature that a great number of head or foot sections may be displayed in a rather restricted floor space.

Another object is to provide a rack which 20 will rather tightly hold a stile of a head or foot section, yet may be operated to quickly and easily release such section if it is to be removed.

A still further object is to provide a display rack which will permit the head or foot 25 sections to be swung horizontally, similarly to the movement of a hinged gate.

With the foregoing in view, the invention 30 resides in the novel subject matter herein-after described and claimed, the description being supplemented by the accompanying drawing.

Figure 1 is a vertical transverse sectional 35 view through the rack, showing the head section of a bed supported in vertical position thereby.

Figure 2 is a fragmentary plan view illustrating a number of head or foot sections 40 held by the rack.

Figure 3 is a view similar to Fig. 2 but illustrating the manner in which the stiles of the head or foot sections may be released from the rack.

Figure 4 is a fragmentary side elevation 45 partly broken away and in section.

Figure 5 is a detail transverse sectional view as indicated by line 5—5 of Fig. 3.

In the drawing above briefly described, 50 the numeral 1 designates a main bar which is preferably formed of wood, the ends of said bar being provided with any appropriate means, such as legs 2, for supporting it in a horizontal position. An upper set of 55 transverse horizontal bars 3 and a lower set of similar bars 4, extend across the upper

and lower edges of the bar 1, are centrally connected with this bar, and project oppositely therefrom, said bars 3 and 4 being spaced apart longitudinally of the bar 1, so 60 that they may receive between them, the stiles of head or foot sections, or both. Preferably, the bars 3 and 4 are pivoted on vertical axes to the bar 1, and the pivots may well be formed of through bolts 5 65 passing through the upper and lower sets of transverse bars and through the main bar 1, the bars of either the upper or the lower set, being thus mounted in vertical alignment with those of the other set. 70

By pivotally mounting the bars 3 and 4, they may assume oblique relation with respect to the bar 1, as indicated in Fig. 2, when one or more head or foot sections are held by them, and when the bars are in this 75 position, they rather tightly engage the stiles of said sections. By swinging the bars 3 and 4 however, until they are substantially at right angles to the bar 1, as indicated in Fig. 3, the spaces between them 80 are widened, so that the stiles are readily freed, permitting the head or foot sections to be easily withdrawn from the rack. It will also be understood that when inserting the stiles of such sections, the transverse bars 85 are positioned as in Fig. 3.

In addition to the advantages above pointed out, attention is directed to the fact that a great number of head or foot sections, or 90 both, may be held in upright position by the rack upon a very restricted floor space. Moreover, these sections may be horizontally swung to any desired positions for exhibiting purposes, and they will not disengage from the rack and tilt, unless they are swung 95 to positions at right angles to the bars 3 and 4.

On account of the excellent results obtainable from the general construction shown, such construction is preferably followed. 100 However, within the scope of the invention as claimed, modifications may of course be made.

I claim:

1. A bedstead exhibitor comprising a main 105 bar having means for supporting it in a horizontal position, a plurality of short transverse horizontal bars spaced apart longitudinally of said main bar and each projecting laterally in opposite directions therefrom to engage said sections at opposite sides of said main bar, said transverse bars 110

being disposed in two vertically spaced sets on the upper and lower faces of the main bar, the bars of one set being in vertical alinement with those of the other set, and 5 a common means connecting each vertically alined pair of transverse bars to said main bar.

2. A bedstead exhibitor comprising a main bar having means for supporting it 10 in a horizontal position, a plurality of short transverse horizontal bars pivoted centrally between their ends on vertical axes to said main bar and spaced apart longitudinally of said main bar, said transverse bars being 15 disposed in upper and lower sets with the bars of one set in vertical alinement with those of the other set, each of said transverse bars projecting in opposite directions from the main bar to engage said sections at opposite sides of said main bar.

20 3. A bedstead exhibitor comprising a

main bar having means for supporting it in a horizontal position, said bar having straight upper and lower edges disposed in parallel planes, a set of short transverse bars resting on the upper edge of the main bar and spaced apart along the same, another set of transverse bars contacting with the lower edge of the main bar directly below the transverse bars of the first named 25 set, each transverse bar of each set projecting in opposite directions from the main bar to engage said sections at opposite sides of the latter, and vertical pivot bolts passing through the transverse bars of the upper and lower sets and through the intervening main bar to pivotally connect the former with the latter.

In testimony whereof I have hereunto affixed my signature.

SAMUEL W. WOMACK.
